UMBRELLA CONSTRUCTION

Wayne S. Evans, Philadelphia, Pa., assignor to
 S. W. Evans & Son, Philadelphia, Pa., a corporation of Pennsylvania

Application August 18, 1933; Serial No. 685,714

6 Claims. (Cl. 135—22)

The object of the invention is to provide improvements in umbrella construction broadly, but more especially in the construction and assembly of each of the structural units. 5 Another object more specifically is to provide improvements in the construction and inter-relation of the stretchers and tongues of each rib unit. Heretofore, when stretchers of U-shaped cross section have been used, whether of plain 10 metallic appearance or coated with paint or enamel, their convex surfaces have been directed upwardly or away from the manually gripped handle portion, and consequently away from the one using the umbrella, thereby causing the concave surfaces to be directed towards the user. 15 However, with an increasing demand for umbrellas in which the stretchers and tongues, as well as the ribs, shaft and other structural elements, are of relative bright appearance in contrast with the color of the fabric covering, it has been found that difficulty and greatly increased 20 costs are experienced, in polishing the concave surfaces of said stretchers and tongues, as when they are nickel, chromium, or otherwise, brightly 25 plated.

A further object is therefore to provide a structure in which the convex instead of the concave surfaces of the stretchers are directed downwardly, or towards the user when the umbrella 30 is in extended or operative position, or away from the shaft when in inoperative or closed position, in combination with substantially flat or ribbon-like tongues which present flat surfaces also adapted to be brightly polished and directed 35 towards the user or the shaft, as the case may be.

Still another object is to provide a construction, which consists in forming the radially outer end of the tongue in the shape of a hook, normally extending thru an aperture in the correspondingly adjacent stretcher, or thru an enlargement of the recess formed by the bifurcation thru which the rib extends, and to the arms of which the rib is actually pivoted, thereby 40 eliminating a rivet or pivot pin in each rib unit, 45 and also facilitating the ease with which the unit is initially assembled or subsequently repaired.

And a still further object is to provide a construction in an automatically extendible umbrella, which permits of the ready repair and/or replacement of parts, and thereby overcoming the great difficulty offered by the highly tensioned 50 spring with which such an umbrella is equipped.

With these objects in mind, the invention comprises further details of construction and operation, which are fully brought out in the follow-

ing description, when read in conjunction with the accompanying drawing, in which

Fig. 1 is a diagrammatic view of the shaft and two diametrically oppositely positioned rib units of an umbrella comprising one embodiment of the invention;

Fig. 2 is a fragmentary view, showing the inter-relation of the shaft, ribs, stretchers and tongues of an automatically extendible umbrella, and bearing in mind that only sufficient portions of the complete structure are shown, to illustrate the principles involved;

Fig. 3 is an enlarged section on the line 3—3 of Fig. 2; and

Fig. 4 is an enlarged fragmentary view, partly in section, of the joint and method of uniting each set of ribs, stretchers and tongues, when in operative or extended relation.

Referring to the drawing, an umbrella is represented as comprising a shaft 1, having a manually engageable portion or handle 2, and carrying upon its normal upper portion rib units, each in turn comprising a rib 3, a stretcher 4 normally under longitudinal compression, and a tongue 5 normally under longitudinal tension. Each rib is hingedly secured at its normal upper and inner end to a collar 6, secured to the shaft in the usual manner, while at a point spaced from said shaft the rib is provided with any desired form of suitably shaped lug 7. The stretcher is of substantially U-shaped cross section (Fig. 3) and as usual has its outer end bifurcated, so as to straddle said lug to which it is pivotally secured by means of a pin 8.

Each tongue in the improved construction is provided with a reversely bent or hooked outer end portion 9, which extends thru the bifurcation of the adjacent stretcher, or thru an aperture in said stretcher spaced from said bifurcation, as may be desired. The radially inner end of each stretcher is pivotally secured to a collar 10 in the usual manner, said last-named collar being slideable upon said shaft, and in its uppermost position being stopped in movement by engagement with a resilient washer 11, of rubber or other suitable material, said washer being operatively positioned by means of a collar 12, which is fixedly secured by means of a pin 13 to said shaft.

Each of said tongues is pivotally secured in the usual manner to a collar 14, which last-named collar may comprise an integral flanged extension of a cylindrical housing 15 for a compression spring 16, and into which housing telescopically slides a second sleeve 17, into which said spring also extends and of which second or inner sleeve 110

said collar 10 may form an integral flanged extension. This spring and telescopic housing does not enter into the present invention, but is of standard and well-known construction, the lower 5 end of the outer housing section being provided with the usual means 18, adapted to engage the resiliently positioned latch 19, which is under control of the manually engageable button 20.

In the operation of the improved construction, 10 with the umbrella in "lowered", or collapsed position the spring is contracted and under relatively high compression between the opposite ends of the two telescopic sleeves, which are then also in contracted position, and in the several rib units 15 the respective ribs, stretchers and tongues are in collapsed parallel relation against and with respect to the shaft. In order to "raise" or extend the umbrella, the button 20 is manually depressed, and the spring thereupon tends to separate the 20 two telescoped sleeves, thereby separating the radially inward ends of the respective pairs of stretchers and tongues, of each rib unit resulting in the extension of the corresponding ribs, and the stretching of the usual cover fabric (not 25 shown) into operative position, where it possesses the normal tension for which it is designed.

In order to repair an umbrella of this construction, the pin 13 is removed and the tension of the spring permitted to force the collars 10 and 12 30 upwardly as far as they will go, whereupon it becomes easy to disengage the hooked portion 9 of as many tongues as desired from their adjacent stretchers. The stretchers also may then be removed and repaired or replaced by separating 35 them from their attached collars 10, after which they are reinstated in the structure, as during the original manufacture. The repaired tongue or tongues, or new ones substituted therefor, are then attached to the collar 14 and their hooked 40 end portions inserted in the adjacent stretchers. The sleeve 17 in uppermost position may then be readily lowered until it begins to enter the larger sleeve 15, after which the collar 12 is re-positioned by inserting the pin 13, and the structure is again 45 ready for use in the customary manner, when a normal downward pull upon the sleeve 15 operates thru the tongues to force the stretchers inwardly and their supporting sleeve 17 also downwardly, bringing the ribs together and gradually 50 telescoping said sleeves and compressing said spring, so as to restore to the structure the original motivating force or tension, whereby the umbrella is again "raised" into operative position when desired.

55 I am aware that the invention may be embodied in other specific forms without departing from the spirit or essential attributes thereof, and I

therefore desire the present embodiment to be considered in all respects as illustrative and not descriptive, reference being had to the appended claims rather than to the foregoing description to indicate the scope of the invention.

Having thus described my invention what I claim and desire to protect by Letters Patent of the United States, is:—

1. In an umbrella, the combination of a 80 stretcher having an opening, and a tongue having a hooked terminal portion, normally removably positioned in said opening.

2. In an umbrella, the combination of a rib, 85 with a lug carried thereby, a stretcher having a bifurcated end portion providing an intervening elongated opening larger than required to accommodate said lug, and a tongue having a hooked terminal portion, normally removably positioned in said opening independently of said lug.

3. In an umbrella, the combination of a 90 stretcher of U-shaped cross section having an opening, and a tongue comprising a transversely flat member having a hooked terminal portion, normally removably positioned in said opening.

4. In an umbrella, the combination of a 95 stretcher of U-shaped cross section, and a tongue pivotally connected thereto, said tongue being transversely flat and the concave side of said stretcher being directed away from said tongue.

5. In an umbrella, the combination of a rib, 100 a stretcher of U-shaped cross section, and a tongue, said stretcher and said tongue being pivotally connected together and to said rib, the concave surface of said stretcher being directed 105 away from said tongue, and said tongue being flat to permit close association with the convex side of said stretcher, when said rib, said stretcher and said tongue are in collapsed or folded position.

6. In an umbrella, the combination of a shaft, 110 a rib pivotally connected thereto; a stretcher and a tongue pivotally connected to said rib, said tongue being in normal hooked engagement with said stretcher, a pair of sleeves slidable upon said shaft, a spring normally separating said 115 sleeves, said stretcher being pivotally connected to one sleeve, and said tongue being pivotally connected to the other sleeve, a stop, means to normally fix said stop to said shaft to limit the separation of said sleeves, said stretcher and 120 tongue, and said stop when shifted, after being released from said means, towards the pivotal connection of said rib with said shaft, permitting the further separation of said sleeves, removal 125 of the tension upon said tongue, and the unhooking of said tongue from said stretcher.
